CLAIM

The ornamental design for a rack for hanging tool, as shown and described.

DESCRIPTION

FIG. 1 is a perspective view of a rack for hanging tool showing my new design;

FIG. 2 is a front elevation view thereof;

FIG. 3 is a rear elevation view thereof;

FIG. 4 is a left side elevation view thereof;

FIG. 5 is a top plan view thereof;

FIG. 6 is a bottom plan view thereof; and,

FIG. 7 is a sectional view thereof along line 7 to 7 of FIG. 2.

The broken lines shown in the drawings depict portions of the article that form no part of the claimed design.

1 Claim, 7 Drawing Sheets
